UNITED STATES PATENT OFFICE

127,294

DESIGN FOR AN ASH RECEIVER

Edgar Collat, Shorewood, Wis.

Application September 24, 1940, Serial No. 95,330

Term of patent 3½ years

To all whom it may concern:

Be it known that I, Edgar Collat, a citizen of the United States and a resident of Shorewood, in the county of Milwaukee, State of Wisconsin, have invented a new, original, and ornamental Design for an Ash Receiver, of which the following is a specification, reference being had to the accompanying drawing, forming part thereof.

Fig. 1 is a plan view of an ash receiver showing my new design,

Fig. 2 is a front elevational view,

Fig. 3 is a side elevational view thereof, while

Fig. 4 is a perspective view thereof.

I claim:

The ornamental design for an ash receiver, as shown.

EDGAR COLLAT.
